UNITED STATES PATENT OFFICE.

J. BENNETT WALLACE, OF CHICAGO, ILLINOIS.

VAPOR-STOVE.

SPECIFICATION forming part of Letters Patent No. 380,611, dated April 3, 1888.

Application filed January 18, 1886. Serial No. 188,817. (No model.)

To all whom it may concern:

Be it known that I, J. BENNETT WALLACE, of Chicago, in the county of Cook and State of Illinois, have invented certain new and useful Improvements in Vapor-Stoves; and I do hereby declare that the following is a full, clear, and exact description thereof, reference being had to the accompanying drawings, and to the letters of reference marked thereon, to which form a part of this specification.

The improvements herein set forth have for their object, first, to provide a better construction and a greater generating efficiency in vapor-generating burners for vapor-stoves, for the purpose more especially of enabling a single generating-burner to effectually provide vapor for itself and for one or more non-generating burners belonging to the same stove.

20 The invention also has for its object to provide an improved construction in distributing-pipes for conveying vapor and air to the non-generating burners of a vapor-stove.

The precise nature of the invention will be 25 more fully understood from the following description of the accompanying drawings and from the appended claims.

In said drawings, Figure 1 is a front elevation of a stove containing my improvements.

30 Fig. 2 is a top view of the generating-burner and the adjacent air and vapor tubes which lead to the non-generating burners of different elevations, the chambered portion of the burner-casting being broken away in horizontal section through the line xx of Fig. 3. Fig. 2^a is a central vertical section of the burner base-plate, its induction vapor-tube, and the surrounding vaporizing-tube in the line zz of Fig. 2. Fig. 3 is a side elevation of the generating-burner having the external, transverse, and pierced boss, which forms a novel feature of the improvement, broken away in vertical section through the line xx of Fig. 2. Fig. 4 is a vertical section of the generating-burner 40 in the plane of line yy , Fig. 2. Fig. 5 is a central vertical section of the tube which conducts air and vapor to the several elevated non-generating burners, showing a butterfly-valve placed in said tube adjacent to and beyond the first of said two burners.

A A are standards of a vapor-stove, and A' is the stove-top.

B is an oven located beneath the stove-top.

C is a generating-burner.

D D' is a tube for vapor and air, leading 55 from near the burner C to the elevated non-generating burners D² D³.

E E' is a second tube leading from a point near the generating-burner C downwardly and beneath the oven B for the supply of vapor 60 and air to the non-generating burner E², located at the bottom of said oven.

E³ is the drip-pan.

It will be seen that the single generating-burner C is employed to supply vapor not 65 only to itself, but to all of the several non-generating burners D², D³, and E² of the stove. The supply of vapor from a single burner to several others in this manner requires that the generating-burner shall be rapid in its 70 generating action and of large capacity, while also desirably of moderate dimensions.

The improvements made in the burner C with the view of securing these ends have for their object to provide a construction which 75 shall give to said burner the highest possible efficiency as a vaporizer, and which shall enable its best product to be supplied equally to either or both of the two pipes which lead to the non-generating burners. To this end the 80 burner is constructed with a cast chambered portion having two compartments, a lateral flange which serves as a base-plate for the burner-cap, a relatively-thin wrought-metal or brass tube leading from one of said compartments to the other around the burner in position to be exposed favorably to the heat of the flame, an opening leading from the stand-pipe into one compartment of the casting, and all of the passages which carry vapor to the 85 several jet-valves leading from the other compartment of said casting, so that all the fluid which is admitted by the stand-pipe makes the entire circuit of the burner through the relatively-thin wrought pipe and is most perfectly 90 vaporized at the point of its escape at either of the jet-valves.

By reference to Figs. 1 and 2 it will be seen that the vapor and air pipes D and E start parallel with each other and longitudinally of 100 the stove, the one continuing directly forward beneath the burners D² and D³, and the other being immediately deflected downward and then forward beneath the oven to the burner

E². It will also be seen from Fig. 1 that the generating-burner C forms one of the burners at the top of the stove, and that in the case of three such elevated burners it stands at the 5 end of the stove, so that its needle or jet valves C³ C⁴, for the control of vapor to the pipes D and E, project also at the end of the stove in convenient positions to be operated and entirely separated from the valve C¹⁰ of the generating-burner itself, which stands at the front of the stove, whereby all confusion on the part of the operator with respect to said valves is obviated.

Turning to Figs. 2, 3, and 4, it will be seen 15 that the chambered casting of the burner is arranged adjacent to the ends of the pipes D and E, and that the partitioned chamber C⁴ of said casting is transverse to the direction of said pipes. C⁴ is the horizontal base-plate, on 20 which rests the cap C'. Said base-plate will ordinarily be cast integral with the chambered portion of the burner-casting, but may be otherwise secured thereto, if desired. The pipe C² rises centrally into said burner-casting and 25 admits the liquid to that which is here shown as the larger compartment of the chamber C⁴, as clearly indicated in Figs. 2 and 3. The partition dividing the chamber C⁴ is shown at c at one side of the opening provided for the 30 stand-pipe C². At opposite ends and at the top of the chambered casting are tubular bosses C⁵, the passages through which communicate with the several compartments of chamber C⁴, and into which are silver-soldered or otherwise tightly fitted the ends of the wrought-metal or brass tube C⁶. Said tube thus forms 35 a continuation of the chamber C⁴, as shown in Fig. 2, and gives the only communication provided between one compartment of said chamber and the other. Through this tube, therefore, the liquid or partially-attenuated vapor admitted by the stand-pipe C² must pass from one to the other of said compartments. From 40 that compartment which is here shown as the smaller, passages lead to all of the several jet-valves, c⁷ being the tube leading to the jet of the generating-burner itself under the control of the needle-valve C¹⁰, and c⁸ the tube or passage leading to the jet-orifice c⁹, through which 45 vapor is supplied to the tube E. By reason of the position of the tube D the jet-orifice c⁹, which is to supply vapor thereto, is located, in the construction shown, at the opposite side of the burner and at the opposite side of the 50 stand-pipe C². To give passage from the smaller compartment of the chamber C⁴ to tube c⁸, which leads to the jet-orifice c⁹, said chamber C⁴ is cut off by a partition, c', which affords a separate chamber, c², in the same 55 casting, and the external transverse boss, C⁵, is provided on the burner-casting, which, by its interior passage, c⁹, gives communication from the said smaller compartment of the chamber C⁴ to the chamber c², as indicated most clearly 60 in Figs. 2, 3, and 4.

The tube c⁴, which leads to the jet-valve of the generating-burner C itself, is shown as

being cast integral with the chambered burner-casting referred to, while the tubes c³ c⁵, which lead, respectively, to the jet-orifices c⁶ c⁹, are 70 shown as being separate from said burner-casting and screw-threaded into the same; but obviously these latter may also be made integral with the chambered casting, or the tube c⁴ may be made separate. These tubes are 75 each provided with the ordinary internally-threaded prolongation, into which its needle-valve C⁸, C⁹, or C¹⁰ is inserted in the axis of the jet-orifice.

For the purpose of increasing the efficiency 80 of the vaporizing or generating tube C⁶, and as a further improvement in my burner, said tube may be silver-soldered or hard-soldered to the margin of the base-plate C⁴, so that the heat of said base-plate is directly communicated to said tube, and the latter is thereby more highly heated than it would be by proximity with the flame itself alone, and particularly is this soldering of the tube to the base-plate important in heating the burner by the 85 auxiliary flame below the base-plate, for in that case the base-plate will be first and most directly heated, and it will more promptly communicate its heat to the tube.

The vapor and air tube D is cast with an 90 upright branch leading to the burner D², and with a horizontal extension, d, reaching beyond said upright branch, into which extension the prolongation D' of said tube D is fitted with sufficient closeness to be practically 95 tight, while also adjustable therein longitudinally, as shown in the sectional Fig. 5. The same extension, d, of the tube D contains the butterfly-valve D⁴, the seat for which is prepared at the same turning or finishing by 100 which said extension, d, is fitted to admit the end of the tube D'. The upright tube leading to the burner D² is not provided with an individual valve, nor is the upright portion of the tube D' provided with such a valve for the 105 use of the burner D². When but one of the burners D² D³ is to be used, it will therefore necessarily be the first burner, D², and the only valve which will need to be operated to supply 110 said burner D² will be the jet-valve controlled by the needle C⁹.

In the use of the burner D² only, the butterfly-valve D⁴ will be turned transversely of the tube D, as shown in said Fig. 5, so as to prevent the passage of vapor to and its escape 115 from the more remote burner, D³; but when both D² and D³ are to be used simultaneously the valve D⁴ will be turned into a horizontal position to allow the vapor and air to pass 120 equally to both of said burners, and the greater 125 amount of vapor required for both burners will be supplied by further opening the jet-valve C⁹. There is no valve in the pipe E or its extension E' for the burner E², since this 130 is the only burner upon this tube, and its supply is wholly controlled by operation of the needle C⁸.

The burners D² D³ and the burner E² may be supported in their proper relation respect-

ively to the stove-top and to the oven by any suitable or ordinary means. The free ends of the tube D and E are shown as being upheld by the bracket F, which depends from the 5 stove-top and is provided with suitable eyes, f f, for the admission of said pipes. In Fig. 2 the upright portion of said bracket F is shown broken off—say in the line x x of Fig. 1. The lower end of the main portion of the 10 tube E is fitted into the enlarged prolongation E' thereof in substantially the same way as illustrated in Fig. 5 of the parts D D' of the horizontal tube. Said prolongation E' is desirably bolted or otherwise fastened to the bottom 15 of the oven B, as indicated at e e in Fig. 1, and thus supports the lower end of the part E. Making the tubes D D' and E E' in two parts with reasonably-close slip-joints, as indicated, contributes to the simplicity of construction 20 by affording a certain amount of adjustment of the parts to each other.

The drip-pan E³ is arranged below the oven, as shown. In this position it affords security against possible discharge of fluid from the 25 oven or burner, and also protects the burner against injury.

G represents the pipe which conveys liquid hydrocarbon from any suitable source of supply to the foot of the stand-pipe C². In the 30 present case the pipe G is supposed to lead from an elevated tank, and is provided with a joint which permits the tank to be raised and lowered in a familiar manner. This is no part of my invention, which is restricted 35 to the matters pointed out in the following claims.

By arranging the non-generating burners D² and D³ in series upon a single pipe with a butterfly-valve immediately after the first of 40 such burners that portion of the pipe beyond the first burner is shut off and kept free of vapor when the second burner is not used.

I claim as my invention—

1. The combination, with a generator located 45 at the end of the stove and provided with a suitable valve for sending vapor to additional burners, of a two-part vapor and air pipe, D D', each part provided with a branch leading to a non-generating burner, the part D thereof 50 being provided with an extension, d, fitted to receive the inserted end of the part D', and provided with a butterfly-valve within said extension d, substantially as described.

2. In a vapor-generating burner, the combination, with a cap having lateral openings 55 for the flame-jets, of a base portion consisting,

first, of a casting having two separate chambers or compartments located at one side of the burner and provided one with an inlet-passage and the other with one or more outlet-passages; second, an apertured bottom plate beneath the cap, and, third, a bent horizontal wrought-metal or brass generating-tube having its ends connected with the several compartments referred to and extending between its ends in position to be heated by the flame-jets, substantially as described. 60

3. A generating - burner having two jet-valves for the supply of vapor to two separate pipes for the conduct of vapor and air to non-generating burners, besides one jet-valve for its own supply, a chambered casting having a partition which separates its chamber into two compartments, an inlet-passage admitting liquid to one of the compartments of said casting, passages leading from the other compartment to the several jet-valves, a base-plate at one side of the casting, a curved wrought-metal tube leading from one chamber to the other of the casting around the margin of the 80 base-plate, and a burner-cap constructed to give a flame adjacent to said tube throughout its length, substantially as described. 75

4. The burner - casting, substantially as shown and described, having the chamber C⁴, 85 divided by partitions c and c', and provided with the pierced boss C⁵, connected with the compartments indicated, a base-plate for the support of an apertured cap, a bent wrought-metal tube encircling the base-plate and connected at its ends into the compartments on opposite sides of the partition c, a jet-valve tube leading from the compartment c², and jet-valve tubes c³ and c⁴, leading from the delivery-compartment cut off by the partition c, 90 substantially as described. 95

5. The combination, in a vapor-generating burner, of a partitioned chambered casting, a base-plate, and a wrought-metal or brass tube having its ends in communication with the 100 compartments of the chambered casting and embracing and soldered to the margin of the base-plate, substantially as described, and for the purposes set forth.

In testimony that I claim the foregoing as my 105 invention I affix my signature in presence of two witnesses.

J. BENNETT WALLACE.
